(57) **CLAIM**

The ornamental design for a lighting device, as shown and described.

DESCRIPTION

FIG. 1 is a front left upper perspective view of a lighting device showing our new design;

FIG. 2 is a front right lower perspective view thereof;

FIG. 3 is a rear right upper perspective view thereof;

FIG. 4 is a rear left lower perspective view thereof;

FIG. 5 is a front side elevational view thereof;

FIG. 6 is a rear side elevational view thereof;

FIG. 7 is a right side elevational view thereof;

FIG. 8 is a left side elevational view thereof;

FIG. 9 is a top plan view thereof; and

FIG. 10 is a bottom plan view thereof; and,

FIG. 11 is a left side elevational view of the lighting device mounted on an example firearm.

The broken lines in the drawings illustrate environmental features and form no part of the claimed design.
